Patented Mar. 10, 1914.

UNITED STATES PATENT OFFICE.

GEORGE F. CONNER, OF PORT HURON, MICHIGAN.

VENDING-MACHINE.

1,089,906.

Specification of Letters Patent. Patented Mar. 10, 1914.

Application filed October 17, 1912. Serial No. 726,196.

To all whom it may concern:

Be it known that I, GEORGE F. CONNER, a citizen of the United States, and a resident of Port Huron, in the county of St. 5 Clair and State of Michigan, have invented a new and useful Vending-Machine, of which the following is a specification.

This invention relates to machines for vending small articles such as chewing gum 10 and confectionery, and its object is to provide a simple and effective coin-controlled vending mechanism which shall be compact, and which shall be made up of few movable parts.

15 In the accompanying drawing Figure 1 is a perspective view of this vending machine. Fig. 2 is a front elevation, with a portion of the front plate broken away to show the movable parts. Fig. 3 is a vertical section 20 on the line 3—3 of Fig. 2. Fig. 4 is a plan of the vending machine with the top plate broken away. Fig. 5 is a section similar to Fig. 3 showing the discharging mechanism in a different position. Fig. 6 is a plan 25 of the locking pawl. Fig. 7 is a detail of the operating shaft. Figs. 8 and 9 are details of construction.

Similar reference characters refer to like parts throughout the several views.

30 The casing is preferably double, and formed of a back 1, bottom 2, partition 3 and sides 4, all preferably integral with each other, or so united as to be substantially integral. The front plate 5 has a 35 top 6 connected to it and a lip 7 extends down within the front flange 8. Side flanges 9 lap over the sides 4, as shown in Fig. 4.

Extending down from the top to the ejecting mechanism of each of the compartments of which two are shown, is a coin-chute 11 whose upper end is immediately below a slot 12 in the top 6. The lower end of this coin-chute is formed of two jaws 13 extending 40 toward each other so as to form a holder for the coins. Extending transversely across through the partition 3 and sides 4, is a two-part operating shaft 14 having an actuating device such as the knobs 15 on its 45 outer ends. Each part of this shaft has secured to it an arm 17 provided with laterally-extending fingers 18, which arm may be mounted on a sleeve 16 on the shaft. A spring 19 normally holds the arm 17 against 50 the back 1 of the case, as shown in Fig. 3. 55 Mounted on the shaft 14 is the ejector which

comprises the side arms 21 and the delivery-table 22 provided with a front flange 23. The front 5 of the case is provided with slots 24 through which these tables may move outward as shown in Fig. 5.

Connected to the back-plate 1 is a lug 25 which supports the pivot 26 of a latch 27, shown in plan in Fig. 6. This latch is provided with an incline shoulder 28 which 60 will engage the cross-plate 29 of the delivery-table and pass through the notch 30 in the same. A spring 32 normally holds the delivery-table 22 in its rearward position, while a spring 31 holds the latch 27 65 against the cross-bar 29.

The operation of this device is as follows: When the front has been removed and small packages or articles 33 placed within the reservoir 34, the front is again positioned, 75 as shown in Fig. 3. Under normal conditions, a knob 15 cannot be turned to turn its respective shaft 14 and swing the delivery-table 22 outward, because this table is held by means of the latch 27 as shown in Fig. 6. 80 When a coin has been dropped through the slot 12, it slides down the chute 11 and rests in the jaws 13. When the arm 17 is swung forward by turning its knob 15, it will strike the rear side of the coin 36, as shown in 85 Fig. 6, and move it forward. The first portion of its movement will slide the coin along the incline 37 of the latch and swing it laterally, as shown in dotted lines in Fig. 6, until the coin rests against the cross-bar 90 29. The coin should be of such size that its upper edge will engage the lowermost of the articles in the reservoir and carry it forward with the delivery-table 22. The side 95 arms 21 extend upward to such a height that their upper edges will support the next-to-the-lowest article in the reservoir, as shown in Fig. 5, until the delivery-table returns to its normal position. The laterally-extending fingers 18 will engage the side 100 arms 21 about the time that the parts assume the position shown in Fig. 5. When the purchaser has swung out the table 22 and the article 33 upon it, he can lift out this article, which movement frees the coin 105 36 which immediately falls to the bottom of the case. Upon releasing the knob 15, the spring 32 is permitted to swing the article ejector back into the case, where it will be held in position by the latch 27 until the 110 next coin is inserted.

The front of the coin-chute 11 is provided

with a slot 38, and a stop-lever 39 is pivoted on the pin 40 on this chute. At the upper end of the stop-lever a lip 41 extends backward so that when the upper end of the lever is swung to the right in Fig. 2, this lip will extend beneath the slot 12 and prevent the introduction of coins. A weight 43 is placed on the articles 33 when the reservoir is filled and has a pin 44 which extends 5 into the slot 38. This pin will engage the lower end 45 of the lever 39 when the last article 33 has been discharged from the case and swing the lip 41 across the slot 12, and thus prevent the introduction of coins after 10 the reservoir is empty. The pin 40 extends rearwardly and may have a small plate 47 secured to it on the rear side of the chute, which plate has fingers 48 between which the upwardly-extending arm of a spring 49 15 extends and normally holds the lever 39 in the position shown in Fig. 2. This spring 49 may be mounted on a pin 50, mounted on the back of the case, as shown in Figs. 3 and 9. 20

25 Any desired lock may be employed to secure the front of the case in position. A very simple lock is shown in Figs. 2 and 4 and consists of a pin 52 carried by the front of the case on which is mounted a dog 53 30 provided with an arm 54, adapted to extend into a hole through the partition 3. A spring 55 normally holds the dog in locking position. A small hole 56 in the top admits the introduction of a wire or other similar tool 35 by means of which the dog can be swung out of engaging position to release the front from the case.

While the ejector arms may be secured to the shaft 14 after the parts are assembled, 40 it may be desirable that the shafts, arms 17 and the delivery tables 22 be assembled before being placed in the case. To permit this, the sides 4 and partition 3 are formed with slots 58 to receive the shafts 14. The 45 flanges 9 on the front are made wide enough to bear against the shafts as shown in Fig. 1, while the tongue 59 is formed on the cover, as shown in Fig. 3, so as to fill the slot in the partition 3. It will be noted 50 that the discharge mechanism will not prevent coins falling to the bottom of the body or case where they will be stored.

While this mechanism has been shown to be in duplicate, it is of course apparent that 55 one side only can be constructed if desired,

and that any desired means may be employed to turn the shaft 14. The other details of construction may be modified to accommodate the machine to packages of different sizes, and the proportions of the parts 60 may all be modified by those skilled in the art without departing from the spirit of my invention as set forth in the following claims.

I claim.

1. In a vending machine, the combination of a case having a slot in its front side, a shaft extending through the case parallel to the front, an ejector mounted on the shaft and adapted to move outwardly 70 through said slot and carry with it one of the articles to be vended, a latch to normally lock the ejector from movement, and an arm secured to said shaft to swing the ejector outward.

2. In a vending machine, the combination of a case having a slot in its front side, a shaft extending through the case parallel to the front, a delivery-table loosely mounted on this shaft and adapted to move outwardly through said slot and carry with it one of the articles to be vended, a latch pivoted at the back of the case and normally engaging the delivery-table to prevent movement, means to turn the shaft, and an arm on the shaft so constructed that it may be swung against the article to be vended and move said article and the delivery-table 80 out of the case.

3. In a vending machine, the combination of a body having a back, a bottom and sides, each of the sides having a slot therein, with a front for the body, said front having side flanges that overlap and inclose portions of the sides of the body, a discharge opening in the front face of the body, and a reservoir for packages adjacent the front face, a shaft mounted to swing in the slots and retained therein by the side flanges of the front, a table secured to the shaft and 95 adapted to swing outwardly through the discharge opening in the front of the body.

In testimony whereof I have signed this specification in the presence of two subscribing witnesses.

GEORGE F. CONNER.
